(57) **CLAIM**

The ornamental design for a display screen with graphical user interface with fantasy sports player information, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a first embodiment of a display screen with graphical user interface with fantasy sports player information showing a first image;

FIG. 2 shows a second image thereof;

FIG. 3 shows a third image thereof;

FIG. 4 shows a front view of a second embodiment of a display screen with graphical user interface with fantasy sports player information showing a first image;

FIG. 5 shows a second image thereof; and,

FIG. 6 shows a third image thereof.

FIGS. 1-3 show a sequence of images that feature a transition from the state shown in FIG. 1 to the state shown in FIG. 3. FIGS. 4-6 show a sequence of images that feature a transition from the state shown in FIG. 4 to the state shown in FIG. 6. The process or period in which one image transitions to another image forms no part of the claimed design. The outermost broken lines show environmental structure and a mobile device having a display screen and do not form any part of the claimed design. The remaining broken lines show portions of the graphical user interface that form no part of the claimed design.
